JOHN HAYS HAMMOND, JR., OF GLOUCESTER, MASSACHUSETTS.

APPARATUS FOR PREDIRECTING AND LAUNCHING TORPEDOES.

Application filed March 20, 1916, Serial No. 85,867. Renewed July 6, 1922. Serial No. 573,187.

To all whom it may concern:

Be it known that I, JOHN HAYS HAMMOND, Jr., a citizen of the United States, and a resident of the city of Gloucester, county of Essex, and State of Massachusetts, have invented certain new and useful Improvements in Apparatus for Predirecting and Launching Torpedoes, of which the following is a specification.

- 10 Some of the objects of this invention are to provide an apparatus for pre-directing and launching torpedoes, improved means for transmitting motion from a periscope or other sighting or aiming device to the 15 steering means of a torpedo to pre-direct the torpedo; to provide improved means for disconnecting the motion transmitting means from the torpedo; to provide means for automatically launching or firing the torpedo 20 after the torpedo has been disconnected from the periscope or other sighting or aiming means; and to provide other improvements as will appear hereinafter.

In the accompanying drawings, Fig. 1 is 25 a diagrammatic elevation partly in vertical section of an apparatus constructed in accordance with this invention, for predirecting and launching torpedoes; and Fig. 2 is a transverse section of the same on line 2—2 30 of Fig. 1.

Referring to the drawings, one embodiment of this invention comprises the usual or any suitable torpedo tube 25, which may be fixed in any suitable position either upon 35 a movable body such as a torpedo boat, or other movable support, or upon any suitable stationary support. Slidably arranged within the torpedo tube 25 is the usual or any suitable torpedo sleeve or carrier 30. 40 In the form shown, the sleeve 30 includes two coaxial tubes 31 and 32 which are rigidly connected by radial partitions or braces 33.

A torpedo 35 is slidably arranged in a well known manner within the inner tube 32 of 45 the sleeve 30. This torpedo 35 may be of any well known or suitable construction, and in the form shown, includes the usual or any suitable outer casing or hollow body portion 36 which is provided with any well known 50 or suitable means (not shown) for propelling the torpedo through the water after it has been launched, and with any well known or suitable means (not shown) for steering the torpedo laterally.

55 The torpedo 35 is also provided with any well known or suitable means arranged to

cooperate with the steering means, and including a gyroscope, or other suitable direction maintaining means (not shown) for automatically causing the torpedo to assume 60 and to be maintained upon a substantially fixed predetermined course after it has been launched.

In the form of this invention shown, the gyroscope or other direction maintaining 65 means for automatically steering the torpedo, is arranged in a casing 39 fixed in the torpedo, and is provided in a well known manner with a rotatably adjustable direction determining element operatively connected 70 to and arranged to be controlled by a stem 40 which projects upwardly through the upper end of the casing 39, and which is rotatable about an axis fixed with respect to the casing 39 and coincident with the longitudinal axis of the stem. By rotating the 75 stem 40, the direction determining element may be adjusted in any desired position so as to cause the torpedo to assume and to be maintained substantially upon any desired 80 substantially straight fixed course after it has been launched.

For predirecting the torpedo 35 by rotating the stem 40 while the torpedo is in its initial inoperative position in the tube 25 (as 85 shown in Fig. 1) a bevel gear 41 is rigidly secured to the upper end of the stem 40, and a bevel pinion 42 engages the bevel gear 41 and is rigidly secured to the inner end 90 of a short horizontal spindle 43 which is rotatively supported in a bearing 44 rigid with the casing 39, and is thus arranged to rotate about an axis fixed with respect to the torpedo 35 and coincident with the longitudinal axis of the spindle. The outer end 95 of the spindle lies within the shell 36 of the torpedo and is provided with a diametrical slot 45 in which fits snugly but removably a flat lug or key 46 which is rigid with the inner end of a cylindrical shaft 50 100 which is coaxial with the spindle 43. The inner portion of this shaft 50 projects snugly but rotatably through apertures 51, 52, 53 and 54 provided therefor in the tubes 25, 31 and 32 and torpedo shell 36. The outer 105 portion of the shaft 50 is rotatably supported in a fixed bearing 60 which is rigidly secured to the torpedo tube 25 by inwardly diverging arms 61.

For pre-directing the torpedo 35 while in 110 its tube 25 by rotatably adjusting the shaft 50 manually, a knurled cylindrical knob 65

is rigidly secured to the outer end of the shaft 50. Coaxial with and rigidly secured to the knob 65 is a dial or disc 66 provided on its periphery with suitable graduations, 5 and pointer or index 67 is fixedly secured to the bearing 60 and has a free end overlapping the disc 66 and arranged to cooperate with the graduations thereon to indicate the adjustment of the shaft 50 and consequently 10 of the gyroscope or other direction maintaining means within the case 39 carried by the torpedo.

For pre-directing the torpedo 35 while in its tube 25 by rotatively adjusting the 15 shaft 50 as the result of the movement of a sighting device, such for instance, as a periscope, telescope, or other device, a pinion 70 is snugly but slidably mounted upon the outer portion of the shaft 50 and is loosely 20 arranged in a recess 71 provided therefor in the fixed bearing 60. The pinion 70 is held against rotation with respect to the shaft 50 by means of a key carried by the pinion and arranged to slide in an elongated key- 25 way 75 in the shaft 50, the construction being such that the shaft 50 may be adjusted rotatively by the action of the pinion 70, and the shaft 50 may be reciprocated in the direction of its longitudinal axis through 30 the pinion 70 while the pinion is held against movement in the same direction by the walls of the recess 71. The pinion 70 is engaged by an idler gear 76 arranged to rotate in either direction about a fixed axis 35 and actuated by a driving gear 77 rigidly secured on the spindle 78 of a fixedly arranged reversible electric motor 79.

For energizing and controlling the motor 79, an annular gear 85 is arranged to 40 rotate in a fixed plane about a fixed axis, and within and secured to this gear is a cylindrical ring 86 of electrical insulation, within and secured to which is a cylindrical ring of conducting material which is divided 45 diametrically by two opposed strips 87 and 88 of insulation forming two approximately semi-circular segmental contacts 89 and 90. Arranged to rotate coaxially with the gear 85 is a spindle 95 which is held against 50 longitudinal movement and which carries a conducting arm 96 insulated as at 97 from the spindle 95 and carrying at its free end a yielding contact 98 arranged to slidably engage alternately the segmental contacts 55 89 and 90. The two segmental contacts 89 and 90 are connected by wires 110 and 111 to the opposite poles of a reversing switch 112 of a well known construction which controls the current from the source 114 of direct 60 electric current through conductors 115 and 116 to the motor 79 to operate the motor in either direction. The reversing switch 112 is provided with a return wire 117 which leads to one pole of a battery 118, the other 65 pole of which is connected by a wire 119 to

the conducting arm 96, the wire 119 being controlled by a switch 120.

Rotary motion is transmitted from the driving gear 77 through a pinion 120 to a stationary electrical transmitter 125 of any well known or suitable construction, by which the rotary motion is transmitted through an electric cable 126 controlled by a switch 127 and to a stationary electrical repeater 130 of any well known or suitable construction which rotates about a fixed axis 75 a pinion 131 which engages and actuates the annular gear 85 to cause the gear to be always rotated in unison with and to the same angular extent as the shaft 50, and in 80 a direction corresponding to the direction of rotation of the shaft 50.

For rotating the spindle 95 in either direction and to any extent desired, an upwardly facing bevel gear 135 is rigidly secured to the upper end of the spindle 95 and is engaged by a bevel pinion 136 which is rigidly secured to the inner end of a cylindrical shaft 137 which is arranged to rotate freely about a horizontal axis coincident 90 with its longitudinal axis in a bearing 138 rigid with a vertically arranged rigid yoke 139 which is arranged to rotate freely about a vertical axis coincident with the longitudinal axis of the spindle 95. The outer portion of the shaft 137 is provided with a handle 140 whereby the shaft 137 may be conveniently rotated manually. The yoke 139 has fixed thereon an index or pointer 141 which travels over a stationary graduated 100 segmental plate 142 to indicate the exact position of the yoke at all times, and also 105 yieldingly presses against the plate 142 to hold the yoke in a fixed position during the operation of the device.

The lower arm of the yoke 139 loosely surrounds the spindle 95, and the upper arm of the yoke 139 carries a downwardly facing bevel gear 145 which engages the bevel pinion 136 and which is arranged to rotate with 110 respect to the yoke 139 about a vertical axis coincident with the axis of rotation of the upwardly facing bevel gear 135. The periphery of the downwardly facing bevel gear 145 is provided with parallel teeth forming 115 a spur gear 146 which is engaged and actuated by a pinion 147 which is arranged to rotate about a fixed vertical axis and which is rotated in either direction about that axis by a stationary electrical repeater 150 of a 120 well known construction. This repeater 150 is rotated in a well known manner in response to energy through an electric cable 151, and switch 152, leading from a primary stationary electrical transmitter 155 of any 125 well known or suitable construction, to which rotary motion may be transmitted in any suitable manner.

In the form of this invention illustrated, rotary motion is transmitted to the primary 130

electrical transmitter 155 and thence eventually to the automatic direction maintaining means 39 of the torpedo 35 through the rotary action of a periscope or other sighting instrumentality 160 which is of well known construction and mounted upon the usual or any suitable support 161 carried by and having a universal movement with respect to the torpedo boat or other carrier 5 of the torpedo 35, the periscope 160 being arranged to rotate about its longitudinal axis. Rigidly secured to the periscope is a gear 162 which drives a pinion 163 fixed upon a rotary shaft 164 by means of which rotary motion is transmitted to the electrical transmitter 155, which is held in a fixed position with respect to the support 161. A graduated disc 165 surrounds and is rigidly secured to the periscope 160 and is arranged 10 to cooperate with an index or pointer 166 rigidly secured to the support 161 to indicate the exact position of the periscope.

For withdrawing the adjusting shaft 50 from the torpedo 35 and torpedo carrier 30, 15 and then immediately thereafter automatically launching or firing the torpedo 35 from the tube 25, this invention provides electrically controlled pneumatic means including a fixed cylinder 175 extending beneath and 20 parallel to the shaft 50, and provided with a piston 176 arranged to reciprocate therein and rigidly secured to the inner end of a piston rod 177, which extends from the piston 176 outwardly in a direction parallel to 25 the shaft 50. Rigidly secured to the outer end of the piston rod 177 and extending upwardly therefrom is a rigid arm 178 which is provided at its upper end with a yoke 179 which engages loosely in an annular recess 30 30 provided therefor in the outer portion of the shaft 50 and embraces the shaft 50 in such a manner as to prevent the rotation of the arm 178 about the axis of the piston rod 177.

35 The shaft 50 is normally held in its innermost or operative position, as shown in Fig. 1 of the drawings, by means of a latch or lever 185 which is arranged to swing about a fixed axis on a pivot 186 carried by the lower arm 61, the latch 185 being arranged 40 to project through a slot 187 in the arm 61. When the shaft 50 and the latch 185 are both in their operative positions, the upper end of the latch 185 engages in an annular recess 189 provided therefor in the shaft 50 and prevents the withdrawal of the shaft.

45 For actuating the latch 185, the lower end of the latch rests slidably against and is movable upwardly independently of the upper end of a vertical piston rod 190, the lower end of which is rigidly secured to a piston 191 arranged to reciprocate in an auxiliary cylinder 192 which is fixedly secured to the main cylinder 175. The pis-

ton 191 is normally held in its lowermost position by a spiral spring in the cylinder 192. The latch 185 is held either in its operative or in its inoperative position by means of a spring pressed catch 195 having 50 a conical upper end which is arranged to engage a pointed lug 196 rigid with the lever 185. The upper end of the auxiliary cylinder 192 is provided with an auxiliary port 194 to facilitate the movement of the 55 piston and to provide an outlet for the inner end of the main cylinder 175 as will appear hereinafter.

For releasing the latch 185 and then moving the piston 176 outwardly to withdraw 60 the shaft 50, the lower end of the auxiliary cylinder 192 is arranged to communicate through an inlet pipe 198 with the interior of a fixed valve casing 199 which surrounds and is controlled by a reciprocating cylindrical piston valve 200 and which is arranged to communicate through a supply pipe 201 with a tank 205 or other source of supply of compressed air. From a point just above the piston 191 when in its lowermost position, and below the piston 191 when in its uppermost position, the auxiliary cylinder 192 communicates through a pipe 206 with the inner end of the main cylinder 175, the arrangement of the pipe 206 being such that 65 the piston 191 will have to be moved upwardly through a distance sufficient to release the latch 185 from the shaft 50 before the piston 191 uncovers the pipe 206 and permits air to flow from the pipe 198 70 through the lower end of the cylinder 192 and into the pipe 206. The outer end of the main cylinder 175 is provided with an exhaust port 210, and the valve casing 199 is provided with an exhaust port 211. 75

80 The valve 200 is provided at its inner end with a collar 212 and is normally pressed inwardly by a spring 213. The valve 200 is also provided with an annular recess 215 so arranged that when the valve is in its 85 outermost position, as shown in Fig. 1, the outer end of the main cylinder 175 and the lower end of the auxiliary cylinder 192 will be free to exhaust through the pipes 210 and 198, annular recess 215, and exhaust 90 port 211, and the supply pipe 201 will be closed by the valve 200, but when the valve 200 is in its innermost position as determined by a collar 217 fixed upon the valve 200, then the lower end of the auxiliary cylinder 192 will be in communication with the 95 source of air supply 205 through the pipe 198, annular recess 215 and supply pipe 201.

100 The valve 200 is normally held in its outermost position by means of a spring 105 pressed soft iron detent 220 which forms the core of a fixed solenoid 221 in which it is arranged to reciprocate, the outer end of the detent being beveled and arranged to engage in a corresponding notch 222 pro-

vided therefor in an extension of the valve 200. The opposite ends of the solenoid 221 are connected to wires 225 and 226 which form a circuit extending through a battery 5 230 or other source of electric energy, and a normally open switch 231 preferably arranged in such a position that it may be readily controlled by an operator while he is making an observation through the peri-

10 scope or other sighting instrument 160.

For automatically admitting compressed air into the inner end of the torpedo tube 25 to fire or launch the torpedo immediately after the shaft 50 has been withdrawn 15 from the tube 25 and moved into its outermost position, a lever 240 is arranged above the shaft 50 to swing about a fixed horizontal axis on a pivot 241 extending through one end of the lever 240 and carried by a 20 projection 242 extending upwardly from the bearing 60. Rigid with and extending downwardly from the lever 240 is a lug 245 having a conical or tapered lower end arranged to engage freely in an aperture 246 25 provided therefor in the bearing 60 and to press against the shaft 50. This lug is so arranged that when the shaft 50 is in its outermost position, the lower end of the lug will fall into the annular recess 189. The 30 free end of the lever 240 is provided with a longitudinal slot 247 which snugly but slidably surrounds a pin 248 rigid with the lower end of a vertical rod 249 which is arranged to reciprocate vertically in a fixed 35 valve case 250. Rigidly secured to this rod 249 is a bar 251, and surrounding the rod 249 between the valve casing 250 and the bar 251 is a compressed spiral spring which presses the rod 249 downwardly. The bar 40 251 is rigidly secured to and actuates a valve 253 which reciprocates vertically in the valve casing 250 and controls the flow of compressed air entering the valve casing 250 from a pipe 254 leading from the source 45 of air supply 205 or other suitable source, and issuing from the valve casing 250 through a pipe 255 leading to the inner end of the torpedo tube 25 and through which air is forced into the inner end of the tor- 50 pedo tube to launch the torpedo in a well known manner.

In the operation of this improved directing and launching mechanism, assuming that the torpedo 35 has been placed in tube 30 with the gyroscopic steering mechanism set in a zero position and with the adjusting shaft 50 connected, as shown in Fig. 1 with the zero graduation of its dial 66 opposite its pointer 67, then, with the 60 switches 120, 127 and 152 of the transmission apparatus open, the periscope 160 is first rotatively adjusted into such a position that the zero graduation of its disk 165 registers with the pointer 166. The yoke 139 65 is then rotatively adjusted into such a posi-

tion that its pointer 141 registers with the zero graduation of the plate 142 where the yoke is permitted to be held in a stationary position by the pressure of the pointer 141 upon the plate 142. The contact arm 96 is 70 then rotatively adjusted so that its yielding contact 98 rests upon the insulation 87, after which the switches 120, 127 and 152 are closed.

If, now, the periscope 160 should be rotated in either direction through a given arc, it will cause the gear 146 to rotate 75 through an equal arc, while the yoke 139 is held in a fixed position by the pointer 141, thus causing the rotation of the gear 80 135 through an arc equal to the arc of rotation of the gear 146 but in an opposite direction. This causes the arm 96 to be rotated so that its yielding contact 98 will move from the insulation 87 and make contact with one 85 of the segments 89 or 90, thus causing the operation of the reversing switch 112 in such a manner as to cause the reversing motor 79 to rotate the shaft 50 in the proper direction. The motor 79 continues to rotate until it has 90 caused the gear 85 to be rotated by the transmitter 125 and repeater 130, through the same angle as the arm 96, whereupon the contact 98 will again be on the insulation 87 and the motor 79 will thus be caused to stop. 95 By means of the gears 42 and 41, the gyroscopic setting mechanism will be caused to move in synchronism with the periscope so that whenever the torpedo is launched it will automatically assume and maintain a course 100 or direction of movement substantially parallel to the line of sight of the periscope.

If, however, it should be desired to have the torpedo assume and maintain a course 105 any given number of degrees either to the right or to the left of the course indicated by the periscope, then, before the torpedo is launched, a suitable initial rotary adjustment of the contact arm 96 may be made by rotating the handle 140 either in one direction or in the opposite direction as the case may be, the gear 146 being held stationary by the repeater 130 during this operation, and a rotation of the yoke 139 through a 110 half a degree being sufficient to rotate the contact arm 96 through a full degree and to predirec the torpedo a full degree either to the right or to the left as the case may be of a course parallel to the course indicated by the periscope in any position into 115 which the periscope may have been turned after such adjustment and before the launching of the torpedo.

After the torpedo has been thus predirected, by the aiming or training of the periscope, and it is desired to fire or launch the torpedo from its tube, it is only necessary for the operator to close the switch 231 thus causing the energization of the solenoid 221, thus releasing the valve 200 which is moved 120 125 130

to the left by the action of spring 213, thus allowing air to pass from the pipe 201 to pipe 198 and enter the cylinder 192. This forces up the piston 191 which causes the 5 lever 185 to be disengaged from the annular recess 189. The air then passes through pipe 206 to the inner end of the cylinder 175, forcing the piston 176 to the right, which causes the shaft 50 to be disengaged 10 from the torpedo and move to the right out of the path of the torpedo and its sleeve 31-32. The lug 245 then drops into the annular recess 189, thus allowing compressed 15 air to pass through the valve casing 250 and to enter into the inner end of the torpedo tube 30 and to launch or fire the torpedo 20 from the tube 25, with the gyroscopic steering mechanism carried by the torpedo so adjusted as to cause the torpedo to assume 25 and to be maintained upon a course predetermined by the periscope at the time of launching.

It is evident from the foregoing that the apparatus or transmission means between 25 the shaft 50 and the periscope 160 might be rendered inoperative by opening the switches 120, 127 and 152, or might be entirely omitted, and the torpedo might then be pre-directed for any desired direction by rotating the knob 65 manually, after which by closing the switch 231 the shaft 50 would be disengaged from the torpedo and the torpedo automatically launched, as hereinbefore described.

35 It is also evident that in case of the failure of the solenoid 221 to perform its function upon closing of the switch 221, it would be possible to depress the detent manually to release the valve 200 and to cause the 40 successive disengagement of the shaft 50 from the torpedo and the launching of the torpedo. In case of the failure of the pneumatic apparatus to perform its function, or in case it is desired to disengage the shaft 45 50 from the torpedo without discharging the torpedo, the latch 185 may be released manually by lifting the outer end of the shaft from the piston 190, and the shaft 50 may then be disengaged manually from the torpedo.

55 Although only a single form has been shown in which this invention may be embodied, it is to be understood that this invention is not limited in its application to any specific construction, but might be embodied in various forms without departing from the spirit of the invention or the scope of the appended claims.

Having thus fully described this invention, I claim:

1. The combination with a support, of motion transmission means for adjusting the steering means of a torpedo while said torpedo is carried by said support, means for locking said transmission means in engage-

ment with said steering means, and means the admission of energy to which is controlled by said locking means for disconnecting said transmission means from said torpedo.

2. The combination with a support, of motion transmission means arranged to adjust the steering means of a torpedo while said torpedo is carried by said support, means for locking said transmission in operative 70 engagement with said steering means, fluid actuated means for releasing said locking means, and means the admission of energy to which is controlled by said fluid actuated 75 means for disengaging said transmission 80 means from said torpedo.

3. The combination with a support, of motion transmission means arranged to adjust the steering means of a torpedo while said torpedo is carried by said support, 85 means for locking said transmission means in operative engagement with said steering means, fluid actuated means for disengaging said locking means from said transmission means, and fluid actuated means the admission of fluid to which is controlled by 90 said first-mentioned fluid-actuated means for disengaging said transmission means from said torpedo.

4. The combination with a support, of 95 means including a shaft rotatable about its longitudinal axis and longitudinally movable for adjusting the steering means of a torpedo when said torpedo is mounted on said support, an element arranged to move 100 into and out of locking engagement with said shaft to lock said shaft in operative engagement with said steering means, fluid actuated means provided with a fluid outlet and arranged to disengage said element 105 from said shaft, and fluid actuated means arranged to receive fluid from said outlet for disengaging said shaft from said steering means after said element has been disengaged from said shaft.

5. The combination with a support, of motion transmission means arranged to adjust the steering means of a torpedo while said torpedo is carried by said support including a shaft rotatable about a fixed axis 115 arranged to reciprocate in the direction of said axis, an element arranged to move into and out of locking engagement with said shaft to hold said shaft in an operative position, fluid-actuated means for releasing said 120 element from said shaft, fluid-actuated means arranged to receive and to be actuated only by fluid receiving through said first-mentioned fluid-actuated means for releasing said shaft from said steering means,

and means including a valve controlled by the longitudinal movement of said shaft for ejecting said torpedo from said support in response to fluid pressure.

6. The combination with a support, of 130

movable sighting means, motion transmission means controlled by said sighting means for adjusting the steering means of a torpedo while said torpedo is carried by said support, said transmission means including two elements rotatable about a common axis supporting means, and means rotatable with respect to said supporting means and carried thereby and arranged to transmit motion from one of said elements to the other of said elements, said supporting means being normally held in a stationary position but being rotatably adjustable about said axis to vary the angular relation between said elements for the purpose of varying the angular relation between said sighting means and said steering means.

7. The combination with a support, of movable sighting means, and motion transmission means controlled by said sighting means for adjusting the steering means of a torpedo while said torpedo is carried by said support, said transmission including two elements rotatable in opposite directions

about the same axis, a support, a member 25 rotatable about an axis fixed with respect to said support for transmitting motion between said elements, said support being normally held in a stationary position but being rotatably adjustable about said first-mentioned axis, an electrical contact carried by one of said elements, a pair of segmental contacts rotatable about said first-mentioned axis and arranged to be alternately engaged by said first-mentioned contact, a 30 reversing switch, three circuits connected to said reversing switch respectively with said contacts, one of said circuits including a source of electrical energy, a motor controlled by said switch, means for energizing said 35 motor, and means controlled by said motor for rotating said segmental contacts about said first-mentioned axis.

Signed at New York city, in the county of New York and State of New York, this 45 15th day of March, A. D., 1916.

JOHN HAYS HAMMOND, JR.
